CONTINUOUS MINING MACHINE

Sterling C. Moon, Dublin, Ohio, assignor, by mesne assignments, to Jeffrey Galion Manufacturing Company, a corporation of Ohio

Filed June 13, 1957, Ser. No. 665,379

21 Claims. (Cl. 262—9)

The instant invention relates to continuous mining machines provided with a mining mechanism at the front end thereof, and means for gathering the mined material and delivering the material to a conveyor, which extends rearwardly along the machine for conveying the material to the rear end of the machine, at which point the material is discharged to a suitable conveyance for taking the material out of the mine, The whole machine being provided with suitable traction means for propelling the machine forward into the face of the mine to continuously remove material therefrom.

It is the prime object of the instant invention to provide an improved continuous mining machine which is of low height and compact construction in order to mine material from low seams in a mine.

It is a further object of the instant invention to provide an improved continuous mining machine of normally low height for the purpose of removing material from low seams in a mine, which can be readily adjusted for mining operations in seams of material which vary widely in height.

It is another object of the instant invention to provide an improved continuous mining machine comprising a mining mechanism for removing material from a mine and a gathering head for collecting the mined material, wherein the mining mechanism is supported on the gathering head and is adjustable with respect thereto.

It is also an object of the instant invention to provide an improved continuous mining machine comprising a mining mechanism for removing material from a mine and a gathering head for collecting the mined material, wherein the mining mechanism is supported on the gathering head, and the latter includes combination gathering and cutting means, with the mining mechanism being adjustable with respect to the gathering head to remove material from the face of a mine in a height of mine face which may be limited to the height of cut of the mining mechanism, or may be adjusted to be equal to the combined height of cut of the mining mechanism and of the cutting means on the gathering head.

It is another object of the instant invention to provide an improved continuous mining machine comprising a conveyor extending the length of the mining machine for discharging the mined material therefrom, and having a head shaft located at the front end of the main frame of the mining machine, there being provided gathering means at the front of the mining machine for collecting mined material, said gathering means being adjustably supported on the main frame of the mining machine on the axis of the conveyor head shaft.

Still another object of the instant invention is to provide an improved continuous mining machine comprising a mining mechanism and a gathering head for collecting the mined material, wherein the mining mechanism is supported on the gathering head and may be vertically adjusted with respect to the gathering head, there being provided baffle means between the mining mechanism and the gathering head to fill the space between the mining mechanism and the gathering head when the mining mechanism is raised, to prevent fouling of the area between the mining mechanism and the gathering head.

A further object of the instant invention is to provide

2

an improved continuous mining machine comprising a gathering head at the front of the machine for collecting mined material, in which the gathering head is pivotally mounted for adjustment relatively to the main frame of the machine, and including driving means for operating the gathering head, said driving means comprising a driving connection disposed on the axis of the pivotal connection of the gathering head to the main frame of the machine.

10 A further object of the instant invention is to provide an improved continuous mining machine having a mining mechanism with cutter elements which extend downwardly therefrom to the floor of the mine, said mining mechanism being supported on a frame member and including spacing means for setting the vertical position of the mining mechanism above the frame member in order to permit substitution of larger cutting elements on the mining mechanism for a greater height of cut.

It is also an object of the instant invention to provide 20 an improved cutting and gathering means for a continuous mining machine comprising a flight which is adapted to sweep mined material from the mine floor and to remove material from the face of a mine in an area adjacent the mine floor.

25 Other objects of the invention will appear hereinafter, the novel features and combinations being set forth in the appended claims.

In the accompanying drawings:

FIG. 1 is a side elevational view of the continuous mining machine of this invention;

FIG. 2 is a top plan view of the continuous mining machine illustrated in FIG. 1;

FIG. 3 is a side elevational view partially in section, showing the mining mechanism and gathering head of the continuous mining machine of this invention;

FIG. 4 is a top plan view of the front end of the continuous mining machine of this invention;

FIG. 5 is a sectional view taken on the line 5—5 in FIG. 4;

FIG. 6 is a side elevational view of the front end of the mining machine similar to FIG. 3 and showing the mining mechanism in elevated position with respect to the gathering head;

45 FIGS. 7 and 8 are side elevational views partially in section of the front end of the novel mining machine, showing the use of spacer blocks to elevate the mining mechanism with respect to the gathering head;

FIG. 9 is a detail view in section showing elements 50 of the driving mechanism for the conveyor and gathering means;

FIG. 10 is a sectional view showing the driving mechanism for operating one side of the gathering means and the discharge conveyor, taken on line 10—10 in FIG. 9, and

55 FIG. 11 is a sectional view in plan showing the connection of the power supplying means to the driving mechanism illustrated in FIG. 10.

Referring to the drawings, the continuous mining machine of the instant invention is generally illustrated in FIGS. 1 and 2. The mining machine comprises a main frame 20 which is supported on endless crawler traction means 21, disposed one at each side of the main frame 20, for propelling the mining machine. A conveyor 22 extends longitudinally along the center of the main frame 20 and serves to discharge the mined material at the rear end of the mining machine, from a material discharge boom section 27 forming the tail end of the conveyor 22. At the front end of the mining machine there is provided a mining mechanism 23 with forwardly projecting cutting means 24, which is adapted to be fed into the face of a mine as the machine is propelled forwardly by the crawler

traction means 21 for removing material from the face of the mine. The mining mechanism 23 is supported on a gathering head 25, which is disposed adjacent the floor of the mine and extends rearwardly and upwardly towards the main frame 20 for delivering the mined material from the floor of the mine to the conveyor 22, which operates to carry the material to the rear end of the mining machine to be discharged from the conveyor boom section 27 at that point. The various elements of the mining machine are operated and controlled from either of twin operator's stations 26, located one at each side of the main frame 20 at the rear end thereof.

The mining mechanism 23 includes a gear box 30 which extends laterally across the front of the mining machine. A plurality of shafts 31 project forwardly from the front face of the gear box 30 in a row extending across the front of the mining machine. At the front end of each shaft 31 there is secured a radially extending cutter arm 32 which is provided with forwardly directed cutter bits 33. The cutter arms 32 are eccentrically mounted on each of the rotary shafts 31, and rotate therewith in circular paths to cut material from the face of the mine. The cutter arms 32 are so disposed with respect to each other as to operate in adjacent overlapping circular paths in order to remove material from substantially the full area of the mine face. Since the cutter arms 32 operate in circular paths, there will remain at the floor and roof of the mine cusps of material. These cusps of material are removed from the roof of the mine by cusp cutters 34, two of which are provided at the front of the mining mechanism 23, extending the full width of the mining mechanism 23. Each of the cusp cutters 34 is provided with a plurality of cutter bits 35 which extend upwardly and forwardly from the top of the cusp cutters 34. An eccentric driving mechanism is provided for operating the cusp cutters 34 to move the cutter bits 35 thereof in small circular paths adjacent the roof of the mine, in order to remove the cusps of material therefrom which are left by the cutter arms 32. The driving mechanism for operating the cusp cutters 34 is not illustrated in detail since it does not form a part of the instant invention. The cutting means for removing the cusps of material from the mine floor will be described in detail hereinafter.

The gear box 30 encloses a suitable gear train for operating the shafts 31, as well as the eccentric driving mechanism for the cusp cutters 34. A pair of transmissions 36 are secured to the rear side of the gear box 30, one at each side of the machine, and are connected to the gear train within the gear box 30 for driving the latter. A pair of drive shafts 37 supply power to the transmissions 36, and these drive shafts 37 extend forwardly from transmissions 38 one at each side of the main frame 20 which are driven by motors supported on the main frame 20 of the mining machine. The shaft 37 is connected at its opposite ends to the transmissions 36, 38 by universal joints 39, and includes a telescoping portion so that the mining mechanism 23 may be readily adjusted with respect to the main frame 20, as will be explained in greater detail hereinafter.

The gathering head 25 extends forwardly from the main frame 20 of the mining machine to adjacent the mine floor. The gathering head 25 comprises a pair of frame members 40 disposed one on each side of the longitudinal centerline of the mining machine. A bridge member 41 extends laterally across the front of the mining machine immediately behind the gear box 30 of the mining mechanism 23. The bridge member 41 is welded, or otherwise secured, to the frame members 40 of the gathering heads 25, and thereby connects the frame members 40.

The bridge member 41 includes a vertical track 42 at each side thereof immediately behind the gear box 30. The rear wall of the gear box 30 is formed with a pair of vertical guides 43 which are complementally formed

with respect to the tracks 42 and are engaged therewith for vertical movement of the mining mechanism 23. The mining mechanism 23 is normally supported by seating on the top surface of the gathering head 25, as best seen in FIG. 3. However, the mining mechanism 23 may be vertically adjusted with respect to the gathering head 25 by movement of the gear box 30 along the tracks 42, which are provided on the bridge member 41 that forms a part of the gathering head 25. Obviously any longitudinal thrust of the mining mechanism 23 is supported or absorbed by the gathering head 25 through said bridge member 41 and said pair of vertical guides 43 and tracks 42. A pair of vertically disposed hydraulic cylinder and piston 44 power mechanisms are provided behind the gear box 30, one adjacent each guide 43. The bottom of each cylinder and piston mechanism 44 is secured to the frame member 40 by a pin 45 (see FIG. 7) and the top of each cylinder and piston mechanism 44 is secured to the gear box 30 by a pin 46 (see FIG. 4).

The mining machine includes a hydraulic system for providing hydraulic fluid under pressure for operating the cylinder and piston mechanisms 44 to elevate the mining mechanism 23 in accordance with the dictates of the mining operation. The hydraulic conduits, connections and other details of the hydraulic system have been omitted from the drawings for the sake of clarity, since these do not form any part of the instant invention.

The frame members 40 of the gathering head 25 extend from adjacent the mine floor rearwardly towards the main frame 20 and upwardly to a position above the conveyor 22. The frame members 40 are disposed one on either side of the longitudinal centerline of the machine and are spaced from each other to form a passageway 47 through which the mined material is moved to the conveyor 22. Each frame member 40 includes a track 48 extending along the passageway 47 and a track 49 extending along the outer side of the frame member 40. At the front of the frame member 40 there is provided a track 50 that extends generally laterally across the front of the machine. The track 50 has rearwardly extending legs 51 at the top and bottom thereof, which fit into slots 52, and the track 50 may be slid forwardly and rearwardly with respect to the frame member 40 for a purpose to be described. A screw element 53 is threaded into the frame member 40 and abuts the rear side of the track 50, and includes an operating collar 54, whereby the screw 53 may be utilized to adjust the position of the track 50.

The gathering head 25 further includes gathering means in the form of a chain 55 of the universal link type which is adapted to pivot in directions at right angles to each other. At regularly spaced intervals along the chain there is linked thereto combination gathering and cutting flights 56 comprising a body portion 57 which is linked to the chain 55 by a pin 58. A first arm 59 extends laterally from the body portion 57 and forms with the body portion 57 (see FIG. 4) a front face 60 for sweeping mined material from the floor of the mine. At the end of the first arm 59 there is provided a plurality of cutter bits 61 which are spaced with respect to each other in an upright line and are also angularly disposed with respect to each other in a diverging pattern. A second arm 62 extends laterally from the body portion 57 of the flight 56 and is disposed behind the first arm 59 in spaced relation thereto. A plurality of cutter bits 63 are secured to the end of the second arm 62 and project forwardly therefrom. The cutter bits 63 are similarly disposed, as are the cutter bits 61 on the first arm 59, except that the cutter bits 63 are alternated with the cutter bits 61 looking in the direction of the chain travel. Referring to FIG. 4, the body portion 57 is seen to comprise a heel 64 at its rear end which abuts a link of the chain 55. The heel 64 is not connected to the chain 55, but by virtue of its bearing against a link of the chain 55, serves to maintain the flight 56 steady as

it travels around the front of the frame member 40 and cuts into the material of the mine. The cutter bits 61, 63 cut material in an area adjacent the mine floor and thereby remove the cusps of material from the mine floor that are left by the cutting means 24.

The frame member 40 has a generally triangular configuration with the apex thereof located near the front end of the conveyor 22. A driving sprocket 65 is disposed at the apex of the frame member 40. The teeth of the sprocket 65 engage the links of the chain 55 to drive the chain around the frame member 40. Since each flight 56 is connected to the chain by a single pin 58, the chain is capable of traveling around the sprocket 65 in a relatively small radius turn. The links 66 of the chain 55 are each formed with upwardly and downwardly extending ears 67 which are engaged in the slots 68 (FIG. 4) of the tracks 48, 49, 50 to thereby guide the chain and maintain the chain steady in its run.

As described above, the cutter arms 32 at the front of the mining mechanism 23 operate in circular overlapping paths which remove material from substantially the whole area of the mine face but leave cusps of material on the floor and roof of the mine. The cutter bits 61, 63 on the flights 56 of the gathering chain 55 operate adjacent the mine floor to remove material from this area and thereby remove the cusps that are formed by the cutting arms 32. The front of each frame member 40 is formed with a blade 70 which is disposed on the mine floor and serves to chip any material that may remain attached to the floor. The blade 70 extends around the front of the gathering head 25 and into the passageway 47. The passageway 47 includes a surface 71 which extends longitudinally upwardly from the mine floor to above the conveyor 22. The surface 71 spans the distance in the passageway 47 between the frame members 40 and provides an uninterrupted, smooth path for the mined material leading to above the conveyor 22. As seen in FIG. 5, the flights 56 travel upwardly along the surface 71 to sweep the material therealong and discharge the material onto the conveyor 22.

The sprocket 65 is keyed to the end of a shaft 72 which is supported in an upwardly extending position in the frame member 40 of the gathering head 25 by suitable roller bearing means (see FIGS. 9 and 10). The shaft 72 has a bevel gear 74 secured thereto by a key 73, the bevel gear 74 being rotated to drive the sprocket 65. The frame member 40 includes a housing 75 for a speed reducing transmission 76 which comprises two pairs of conventional spur gears. A bevel gear 77 is driven by the transmission 76, and this bevel gear 77 meshes with the bevel gear 74 to rotate the shaft 72 for driving the sprocket 65. The transmission 76 is driven by a drive shaft 78, at the outer end of which there is keyed a bevel gear 79. The bevel gear 79 is driven by a bevel gear 80 which is driven through a clutch mechanism 81, powered by a shaft 82 (see FIG. 11). The outer end of the shaft 82 includes a universal joint 83 which connects the end of drive shaft 84 thereto. The other end of the drive shaft 84 is connected by a universal joint 85 to the transmission 38 which supplies the power for driving the various operating elements, including the drive shaft 78 and the bevel gear 74, that rotate the sprocket 65.

The front of the main frame 20 is formed with a pair of cylindrical sockets 88 (FIG. 10) located one on each side of the main frame 20, and these sockets 88 support the gathering head 25 on the front end of the main frame 20. Each frame member 40 of the gathering head 25 is formed with a hollow cylindrical journal 89 extending to the opposite sides of the gathering head 25 and fitting into the sockets 88. The journal 89 is spaced from the socket 88 by a sleeve bushing 90 to provide a bearing between the journal 89 and the socket 88. The sockets 88 at the opposite sides of the main frame 20 pivotally support the gathering head 25 on the front end of the

main frame 20, with the journals 89 being adapted to pivot relatively to the sockets 88, so that the gathering head 25 may be adjusted about the normally horizontal transverse axis of the pivotal connection for adjustment of the gathering head 25 relatively to the main frame 20. It is obvious that any longitudinal thrust on the gathering head 25, either directly or through the mining mechanism 23, bridge 41, etc., will be transmitted to the supporting main frame 20 through the sockets 88, journals 89 and bushings 90.

10 The drive shaft 78 is disposed within the hollow journal 89 with the axis thereof coincident with the axis of the pivotal connection of the gathering head 25 to the main frame 20. The end of the drive shaft 78, which connects to the transmission 76 is rotatably supported by a ball bearing 91 mounted on the housing 75 of the frame member 40. The opposite end of the drive shaft 78, which has secured thereto the bevel gear 79, is supported by a ball bearing 92 mounted in a collar 93 which, in turn, is bolted to the main frame 20. Thus, the drive shaft 78 may continuously rotate while the gathering head 25 is pivotally adjusted relatively to the main frame 20 on the pivotal connection formed by the journals 89 and the sockets 88. The transmission 76 and the bevel gears 74, 77 which drive the sprocket 65 are all mounted 20 in the frame member 40 of the gathering head 25, and move therewith when the gathering head 25 is adjusted relatively to the main frame 20.

25 At either side of the main frame 20 an arm 95 extends outwardly and forwardly in the direction of the gathering head 25. The arm 95 extends a substantial distance forwardly of the pivotal connection between the gathering head 25 and the main frame 20 to a position near the top of the mining machine. The front end of 30 each arm 95 has a cylinder and piston mechanism 96 secured thereto by a pin 97. The cylinder and piston mechanism 96 extends downwardly from the front end of the arm 95, and has the lower end thereof secured to the gathering head 25 by means of a pin 98 connecting 35 the cylinder and piston mechanism 96 to the gathering head 25 through a laterally extending bracket 99. Suitable hydraulic connections leading from the hydraulic system of the mining machine connect to the cylinder and piston mechanism 96 for operating it in the usual 40 manner to contract or expand the device. These are not illustrated in the drawings for the sake of clarity since they do not form any part of the instant invention. The cylinder and piston mechanism 96 may be contracted to 45 pivot the gathering head 25 on the axis of the socket 88 on the main frame 20, to raise or lower the gathering head 25 at the front end of the mining machine in accordance with the dictates of the mining operation. Since 50 the mining mechanism 23 is supported on the gathering head 25, it will also be raised and lowered with the gathering head 25 when the cylinder and piston mechanism 96 is operated. To this extent the mining mechanism 23 and the gathering head 25 form a single unit in 55 the machine.

55 The conveyor 22, which receives the mined material 60 from the gathering head 25, extends from the front end of the main frame 20 rearwardly along the longitudinal centerline of the mining machine to the rear end thereof at which point the material is discharged from the boom section 27. The conveyor 22 comprises a universal linked 65 chain 100 having laterally extending flights 101 located at regularly spaced intervals along the length of the chain. The conveyor 22 includes a conveyor bed 102 over which the flights 101 sweep the mined material, and 70 a chain guide 203 (FIG. 4) disposed on the conveyor bed 102 for guiding the chain 100 in a straight run. The receiving end of the conveyor 22 at the front of the main frame 20 has a laterally extending shaft 103 (FIG. 5) formed with a sprocket 104. The sprocket 104 is driven 75 by the shaft 103 and the teeth of the sprocket 104 en-

gage the links of the chain 160 to drive the chain along the bed 162.

The head shaft 103 of the conveyor 22 is rotatably supported between the frame members 40 of the gathering head 25. The opposite ends of the shaft 103 are rotatably mounted within ball bearings 105 which, in turn, are mounted within supporting collars 106 bolted to the frame members 40. The ends 107 of the shaft 103 extend beyond the bearings 105 and each end 107 of the shaft 103 has fixedly secured thereto a bevel gear 108 which meshes with the gear 74 that rotates the shaft 72 and the sprocket 65 for the gathering means. The drive for the shaft 103 and sprocket 104 of the conveyor 22 is thus directly tied to the drive for the gathering means on the gathering head 25. It is a further characteristic of the drive that the head shaft 103 is rotatably supported by the bearings 105 on the frame members 40 of the gathering head 25, and the axis of the head shaft 103 is coincident with the axis of the drive shaft 78, and the axis of the pivotal connection of the gathering head 25 to the main frame 20 formed by the socket 88 and the journal 89. Accordingly, the gathering head 25 may be freely pivoted in the sockets 88 of the main frame 20, without in any way affecting the driving connection to the head shaft 103 of the conveyor 22. The machine can operate continuously while the gathering head 25 is pivotally adjusted relatively to the main frame 20.

As previously described, the mining mechanism 23 may be vertically adjusted on the tracks 42 to raise it with respect to the gathering head 25 by operation of the cylinder and piston mechanisms 44. When the mining mechanism 23 is adjusted in this manner, it will be spaced above the top of the frame members 40 of the gathering head 25. The space, thus formed between the mining mechanism 23 and the top of the frame members 40, would have a tendency to be fouled by dust and mined material that would fly into the space during the course of the mining operation. Accordingly, a baffle 110 (see FIG. 6) is provided between the mining mechanism 23 and the gathering head 25.

Two baffles 110 are provided, one on either side of the machine, for each frame member 40. The frame member 40 is formed with a hollow socket 111 that extends laterally under the mining mechanism 23 and is of elongated configuration with rounded ends. Telescoped within the socket 111 are a first baffle member 112 and a second baffle member 113, both parts of gathering head 25. The first baffle member 112 is secured to the underside of the gear box 30 of the mining mechanism 23 by bolts 114. The bottom of the first baffle member 112 is formed with a peripheral flange 115 that engages under a lip 116 at the top of the second baffle member 113. The first baffle member 112 is of such size that it will telescopically fit within the second baffle member 113, and when the first baffle member is raised, the flange 115 thereof will engage behind the lip 116 on the second baffle member 113 to withdraw it from the socket 111 in an upward direction. The second baffle member 113 is formed with a peripheral flange 117 which is adapted to engage under a lip 118 formed at the top of the socket 111 in the frame member 40. Thus, as the mining mechanism 23 is elevated with respect to the gathering head 25, the gear box 30 will withdraw the first baffle member 112 from within the second baffle member 113. As the mining mechanism 23 is raised further, the baffle member 112 will engage the second baffle member 113 by means of the flange 115 abutting under the lip 116, and then the second baffle member will be withdrawn from the socket 111 as illustrated in FIG. 6. The first and second baffle members 112, 113 will substantially fill the space between the gear box 30 of the mining mechanism 23 and the top of the frame members 40 of the gathering head 25. Thus, dust and particles of mined material cannot lodge in this space and foul the mecha-

nism to prevent lowering the gear box 30 onto the top of the frame members 40.

When the mining mechanism 23 is in its lowermost position, as shown in FIG. 3, the cutter arms 32 extend downwardly to the floor of the mine in front of the flights 56 on the gathering chain 55. With this arrangement the gathering means in effect follows the cutting arms 32 of the mining mechanism 23 to collect the mined material. The cutting bits 61, 63 on the flights 57 are operative to cut an area adjacent the mine floor and will remove the cusps along the mine floor which are left by the rotating cutter arms 32 which cut in overlapping circular paths. The mining machine of this invention is normally adapted to mine material in a relatively low height seam and it is so adapted by the arrangement of the mining mechanism 23 and the gathering head 25 as described herein. The mining machine is capable of adjustment to mine material in higher seams as well, and one such adjustment is provided by the cylinder and piston mechanism 44 at the rear of the mining mechanism 23, which is operative to elevate the mining mechanism 23, as shown in FIG. 6. When the mining mechanism 23 is so elevated with respect to the gathering head 25, the cutter arms 32 will extend downwardly to the top of the flights 57 and the cutter bits 61, 63. With the mining machine so adjusted the cutter arms 32 will mine material from an area of the mine face that is spaced above the mine floor, and the cutter bits 61, 63 will remove the material along a height of the mine face extending from the floor of the mine to the bottom of the cutter arms 32. The cutter bits 61, 63 on the flights 57 travel around the frame members 40 and into the passageway 47 formed between the frame members 40, and thus will remove the material in this area also as they travel around the frame members 40. The surface 71 in the passageway 47 is formed with a blade 69 at its front end (see FIG. 5), and this blade 69 is so disposed relative to the mine floor to chip away any rib of material that may be left by the spacing between the two gathering and cutting chains and flights 55, 56.

The mining machine of this invention may be adapted for mining in seams which are of greater height than the range of adjustment described above. For this purpose there is provided a set of spacer blocks 120, 121, which may be interposed between the gear box 30 of the mining mechanism 23 and the frame members 40 of the gathering head 25. The spacer block 120 is of an intermediate size and the spacer block 121 is of a larger size, and these are illustrated in FIGS. 7 and 8 as being exemplary of various size spacer blocks that may be utilized in the mining machine of this invention. As seen in FIG. 7, the spacer block 120 is placed between the bottom surface of gear box 30 and the top surface of the first baffle member 112 (which is part of the head 25), and secured therebetween by suitable size bolts 122. In order to give the greater height of cut on the mine face, intermediate size cutter arms 123 are substituted on the rotatable shafts 31 in place of the smaller size cutter arms 32. The intermediate size cutter arms 123 will travel in a circular path of greater diameter than that of the smaller cutter arms 32 and thereby remove material from a greater height on the mine face. As previously described, the mining mechanism 23 may be vertically adjusted with respect to the gathering head 25 to give a full height of cut which is equal to the sum of the height of cut of the cutting arms 123 and of the cutter bits 61, 63 on the gathering flights 57.

If a still greater height of cut is desired a larger spacer block 121 may be utilized, and this is secured between the gear box 30 and the first baffle member 112 by suitable size bolts 124 (see FIG. 8). Larger cutter arms 125 are substituted on the rotary shafts 31 to provide the greater height of cut on the face of the mine, and as previously, the gear box 30 may also be elevated by means

of the cylinder and piston mechanism 44 to further increase the height of cut in the mine.

The whole mining machine of this invention is supported on traction means 21 which comprises endless crawler treads 126 disposed one at either side of the main frame 20 and adapted to be independently driven so that the machine may be propelled around a curve. A sprocket wheel 127 at the front end of the main frame 20 guides the front end of the crawler tread 126 and also drives the crawler tread 126 by engagement of the sprocket tooth with the links of the crawler tread 126. An idler sprocket wheel 128 is disposed adjacent the rear of the main frame 20 and guides the rear end of the crawler tread 126. Behind the driving sprocket wheel 127 there is provided a shoe 129 (see FIG. 8) which is generally flat and extends rearwardly behind the driving sprocket wheel 127 to guide the crawler tread 126 with a floor engaging portion of the tread 126 bearing against the shoe 129. The shoe 129 is pivotally mounted on a pivot pin 130 and may be swung downwardly about this pivot. The shoe 129 has a head end 131 and a flat intermediate portion 132 which are normally in engagement with the crawler tread 126 to guide the same. The shoe 129 further includes a heel 133 that is normally disposed above the crawler tread 126 and curves upwardly from the flat intermediate portion 132 of the shoe 129. Above the heel 133 there is formed a bracket 134 to which there is pivotally secured a cylinder and piston mechanism 135 by a pin 136. The upper end of the cylinder and piston mechanism 135 is secured to the main frame 20 by a pin 137.

The shoe 129 can be pivotally adjusted about the pivot pin 130 by operation of the cylinder and piston mechanism 135, operation of which will lower the heel portion 133 into engagement with the crawler treads 126 and raise the head portion 131. The effect of this operation is to change the path of the crawler tread 126 and to extend it further downwardly, which will result in raising the machine with respect to the floor of the mine. The shoes 129 on the opposite sides of the mining machine are independently operable and thus may be utilized to provide a lateral adjustment of the machine to maintain the machine level in a lateral direction irrespective of the contour of the mine floor, which will usually be somewhat uneven. The effect of this adjustment is to provide a lateral tilting of the mining mechanism 23 at the front of the mining machine to maintain it level in a lateral direction.

From the foregoing description it is apparent that the continuous mining machine of this invention is a compact machine which is particularly adapted for mining operations in low seams of material. The mining machine comprises a mining mechanism located at the front of the machine and supported on a gathering head which collects the mined material from the mine floor and delivers it to a conveyor which extends rearwardly along the longitudinal centerline of the machine to move the material to the rear of the machine where it is discharged. The gathering head is supported on the front end of the main frame of the mining machine on pivot means which permits the gathering head to be adjusted upwardly and downwardly in order to follow the seam of material in the mine. The mining mechanism being supported on the gathering head is similarly adjusted along with the gathering head. The mining mechanism of the machine is capable of further adjustment with respect to the gathering head and independently thereof for mining in higher seams of material.

The gathering means on the gathering head includes cutter elements which are adapted to remove material from an area adjacent the mine floor, and the mining mechanism can be raised with respect to the gathering head so that the cutter elements thereof will remove material from an area above the aforementioned cutter elements on the gathering means, thereby increasing the

effective cutting height of the machine. The cutting height of the mining machine of this invention may be further increased by spacing the mining mechanism above the gathering head and substituting larger cutter elements on the mining mechanism. As another feature of the novel mining machine of this invention, the drive for the gathering means and the drive for the conveyor, which discharges the mined material from the machine, are interconnected along the axis of the pivotal connection of the gathering head to the main frame of the machine, thereby providing a compact drive for these elements of the machine.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. In a continuous mining machine having a main frame supported on traction means for propelling the mining machine and a mining mechanism at the forward end of the mining machine for removing material from the face of a mine, a gathering head at the front of the mining machine including gathering means disposed adjacent the floor of the mine for collecting the mined material from the mine floor, means adjustably supporting the mining mechanism on the gathering head at the front of the machine and above the gathering means, means for raising and lowering the mining mechanism relatively to the gathering head to adjust the position of the mining mechanism, baffle means disposed within the gathering head, said baffle means being secured to the mining mechanism and raised therewith from the gathering head to fill the space between the mining mechanism and the gathering head, means for adjustably supporting said gathering head and said mining mechanism on the main frame, and means for adjusting the gathering head and the mining mechanism relatively to the main frame.

2. In a continuous mining machine having a main frame supported by traction means for propelling the mining machine and a mining mechanism at the forward end of the mining machine for removing material from the face of a mine, gathering head at the front of the mining machine including gathering means disposed adjacent the floor of the mine for collecting the mined material from the mine floor, means adjustably supporting the mining mechanism on the gathering head at the front of the machine and above the gathering means, means for raising the mining mechanism relatively to the gathering head to adjust the position of the mining mechanism, baffle means disposed between the mining mechanism and the gathering head, said baffle means comprising a plurality of telescoping members disposed within the gathering head when the mining mechanism is in its lowermost position, means securing said baffle means to the mining mechanism to be extended when the mining mechanism is raised relatively to the gathering head to fill the space between the mining mechanism and the gathering head, means for adjustably supporting said gathering head and said mining mechanism on the main frame, and means for adjusting the gathering head and the mining mechanism relatively to the main frame.

3. In a continuous mining machine having a main frame supported on traction means for propelling the mining machine and a mining mechanism at the forward end of the mining machine for removing material from the face of a mine, a gathering head at the front of the mining machine including gathering means adapted to be disposed adjacent the floor of the mine for collecting the mined material from the mine floor, means adjustably supporting the mining mechanism on the gathering head at the front of the machine and above the gathering

means, means for raising the mining mechanism relatively to the gathering head to adjust the position of the mining mechanism, baffle means disposed in the gathering head, said baffle means being secured to the mining mechanism and raised therewith to fill the space between the mining mechanism and the gathering head.

4. In a continuous mining machine having a main frame supported on traction means for propelling the mining machine and a mining mechanism at the forward end of the mining machine for removing material from the face of a mine, a supporting frame member at the front of the mining machine, means adjustably supporting the mining mechanism on the supporting frame member at the front of the machine and above the supporting frame member, means for raising the mining mechanism relatively to the supporting frame member to adjust the position of the mining mechanism, baffle means disposed in the supporting frame member, said baffle means being secured to the mining mechanism and raised therewith to fill the space between the mining mechanism and the supporting frame member.

5. In a continuous mining machine comprising traction means for propelling the mining machine and a mining mechanism for removing material from the face of a mine, a supporting frame member, means adjustably supporting the mining mechanism on the frame member, means for raising and lowering the mining mechanism relatively to the supporting frame member to adjust the position of the mining mechanism, baffle means disposed in the supporting frame member, and means for raising and lowering the baffle means with the mining mechanism to fill the space between the mining mechanism and the supporting frame member.

6. In a continuous mining machine comprising traction means for propelling the mining machine and a mining mechanism for removing material from the face of a mine, a supporting frame member, means adjustably supporting the mining mechanism on the supporting frame member, means for raising and lowering the mining mechanism relatively to the supporting frame member to adjust the position of the mining mechanism, baffle means disposed between the mining mechanism and the supporting frame member, said baffle means comprising a plurality of telescoping members disposed within the supporting frame member when the mining mechanism is in its lowermost position, means securing said baffle means to the mining mechanism to extend the baffle means when the mining mechanism is raised relatively to the supporting frame member to fill the space between the mining mechanism and the supporting frame member.

7. In a continuous mining machine having a mining mechanism for removing material from the face of a mine and means to propel the mining machine, gathering means for collecting the mined material comprising a chain and means for driving the chain through the mined material, a combination gathering and cutting flight on the chain, said flight comprising a body portion linked to the chain and extending laterally therefrom, said body portion being formed with a front face for sweeping the mined material, a first row of spaced cutter bits arranged substantially in an upright row projecting from the body portion, a second row of spaced cutter bits arranged substantially in an upright row disposed behind said first row of cutter bits and projecting from the body portion, the cutter bits in said second row being alternated with the cutter bits in said first row in the direction of travel of said chain.

8. In a continuous mining machine having a mining mechanism for removing material from the face of a mine and means to propel the mining machine, gathering means for collecting the mined material comprising a combination gathering and cutting flight adapted to be driven through the mined material, said flight being formed with a front face for sweeping the mined material, a first row of spaced cutter bits arranged substantially in an upright

row projecting from the flight, a second row of spaced cutter bits arranged substantially in an upright row disposed behind said first row of cutter bits and projecting from the flight, the cutter bits in said second row being alternated with the cutter bits in said first row in the direction of travel of the flight.

9. In a continuous mining machine having a mining mechanism for removing material from the face of a mine and means to propel the mining machine, gathering means for collecting the mined material comprising a combination gathering and cutting flight adapted to be driven through the mined material, said flight being formed with a front face for sweeping the mined material, a first row of spaced cutter bits arranged substantially in an upright row projecting from the flight, a second row of spaced cutter bits arranged substantially in an upright row disposed behind said first row of cutter bits and projecting from the flight, the cutter bits of each of said rows projecting from the flight in a direction substantially parallel to said front face.

10. In a continuous mining machine having a main frame supported on traction means for propelling the mining machine and a mining mechanism at the forward end of the mining machine for removing material from the face of a mine, a gathering head at the front of the mining machine including gathering means adapted to be disposed adjacent the floor of the mine for collecting the mined material from the mine floor, said gathering means comprising a combination gathering and cutting flight adapted to be driven through the mined material, said flight being formed with a front face for sweeping the mined material, a first row of spaced cutter bits arranged substantially in an upright row projecting from the flight, a second row of spaced cutter bits arranged substantially in an upright row disposed behind said first row of cutter bits and projecting from the flight, the cutter bits in said second row being alternated with the cutter bits in said first row in the direction of travel of the flight, means adjustably supporting the mining mechanism on the gathering head at the front of the machine and above the gathering means, means for raising the mining mechanism relatively to the gathering head to adjust the position of the mining mechanism to cut an area of the mine face above that cut by the gathering means cutter bits, baffle means disposed between the mining mechanism and the gathering head, said baffle means being secured to the mining mechanism and raised therewith to fill the space between the mining mechanism and the gathering head.

11. In a continuous mining machine having a main frame supported on traction means for propelling the mining machine and a mining mechanism at the forward end of the mining machine for removing material from the face of a mine, a gathering head at the front of the mining machine including gathering means adapted to be disposed adjacent the floor of the mine for collecting the mined material from the mine floor, said gathering means comprising a combination gathering and cutting flight adapted to be driven through the mined material, said flight being formed with a front face for sweeping the mined material, a first row of spaced cutter bits arranged substantially in an upright row projecting from the flight, a second row of spaced cutter bits arranged substantially in an upright row disposed behind said first row of cutter bits and projecting from the flight, the cutter bits of each of said rows projecting from the flight in a direction substantially parallel to said front face, means adjustably supporting the mining mechanism on the gathering head at the front of the machine and above the gathering means, means for raising the mining mechanism relatively to the gathering head to adjust the position of the mining mechanism to cut an area of the mine face above that cut by the gathering means cutter bits, baffle means disposed between the mining mechanism and the gathering head, said baffle means being secured to the mining mechanism and raised

therewith to fill the space between the mining mechanism and the gathering head.

12. In a continuous mining machine having a main frame supported on traction means for propelling the mining machine and a mining mechanism at the forward end of the mining machine for removing material from the face of a mine as the mining mechanism is advanced into the mine face, a gathering head including gathering means for collecting the mined material from the mine floor, means supporting the mining mechanism on the gathering head including a top surface on the gathering head for seating the mining mechanism on the gathering head, said mining mechanism being disposed above the gathering head and being seated on the gathering head on said top surface, said gathering head including a frame member disposed behind the mining mechanism, means on said frame member and mining mechanism connecting the mining mechanism to the frame member to support the longitudinal thrust of the mining mechanism on the gathering head as the mining mechanism is advanced into the mine face, means for supporting said gathering head and said mining mechanism on the main frame, the last said supporting means including pivot means pivotally connecting the gathering head and the mining mechanism to the main frame and supporting the gathering head and the mining mechanism on the main frame for transmitting the longitudinal thrust of the mining mechanism from the gathering head to the main frame, and means for pivoting the gathering head and the mining mechanism on said pivot means to adjust the gathering head and the mining mechanism relatively to the main frame.

13. In a continuous mining machine having a main frame supported on traction means for propelling the mining machine and a mining mechanism at the forward end of the mining machine for removing material from the face of a mine as the mining mechanism is advanced into the mine face, a gathering head at the front of the mining machine including gathering means disposed adjacent the floor of the mine for collecting the mined material from the mine floor, means supporting the mining mechanism on the gathering head at the front of the machine and above the gathering means including a top surface on the gathering head for seating the mining mechanism on the gathering head, said mining mechanism being disposed above the gathering head and being seated on the gathering head on said top surface, said gathering head including a frame member disposed behind the mining mechanism, means on said frame member and mining mechanism connecting the mining mechanism to the frame member to support the longitudinal thrust of the mining mechanism on the gathering head as the mining mechanism is advanced into the mine face, means for adjustably connecting said gathering head and said mining mechanism to the main frame and supporting the gathering head and the mining mechanism on the main frame for transmitting the longitudinal thrust of the mining mechanism from the gathering head to the main frame, and means for adjusting the gathering head and the mining mechanism relatively to the main frame.

14. In a continuous mining machine having a main frame supported by traction means for propelling the mining machine and a mining mechanism at the forward end of the mining machine for removing material from the face of a mine as the mining mechanism is advanced into the mine face, a gathering head at the front of the mining machine including gathering means disposed adjacent the floor of the mine for collecting the mined material from the mine floor, said gathering means including cutter means to cut an area of the mine face adjacent the floor of the mine, means for supporting the mining mechanism on the gathering head including a top surface on the gathering head for seating the mining mechanism on the gathering head, said mining mechanism being disposed above the gathering head and being seated on the gathering head.

on the gathering head on said top surface, said gathering head including a frame member disposed behind the mining mechanism, track and guide means on said frame member and mining mechanism connecting the mining mechanism to the frame member for adjustment of the mining mechanism relatively to the gathering head and to support the longitudinal thrust of the mining mechanism on the gathering head as the mining mechanism is advanced into the mine face, said mining mechanism including cutter means extending down in front of the gathering means, means for raising the mining mechanism above the gathering head to adjust the mining mechanism cutter means relatively to the gathering head for removing material from the area of the mine face above the area thereof from which the cutter means on the gathering means removes material.

15. In a continuous mining machine having a main frame supported by traction means for propelling the mining machine and a mining mechanism at the forward end of the mining machine for removing material from the face of a mine as the mining mechanism is advanced into the mine face, a gathering head at the front of the mining machine including gathering means disposed adjacent the floor of the mine for collecting the mined material from the mine floor, said gathering means including cutter means to cut an area of the mine face adjacent the floor of the mine, means adjustably supporting the mining mechanism on the gathering head including a top surface on the gathering head for seating the mining mechanism on the gathering head, said mining mechanism being disposed above the gathering head and being seated on the gathering head on said top surface, said gathering head including a frame member disposed behind the mining mechanism, track and guide means on said frame member and mining mechanism connecting the mining mechanism to the frame member for adjustment of the mining mechanism relatively to the gathering head and to support the longitudinal thrust of the mining mechanism on the gathering head as the mining mechanism is advanced into the mine face, said mining mechanism including cutter means extending down in front of the gathering means, means for raising the mining mechanism above the gathering head to adjust the mining mechanism cutter means relatively to the gathering head for removing material from the area of the mine face above the area thereof from which the cutter means on the gathering means removes material.

16. In a continuous mining machine having a main frame supported by traction means for propelling the mining machine and a mining mechanism at the front end of the mining machine for removing material from the face of a mine as the mining mechanism is advanced into the mine face, a gathering head at the front of the mining machine including gathering means disposed adjacent the floor of the mine for collecting the mined material from the mine floor, means supporting the mining mechanism on the gathering head including a top surface on the gathering head for seating the mining mechanism on the gathering head, said mining mechanism being disposed above the gathering head and being normally seated on the gathering head on said top surface, said gathering head including a frame member disposed behind the mining mechanism, means on said frame member and mining mechanism for connecting the mining mechanism to the frame member for upright adjustment of the mining mechanism relatively to the gathering head and to support the longitudinal thrust of the mining mechanism on the gathering head as it is advanced into the mine

face, said mining mechanism including cutter means extending down to the mine floor in front of the gathering means, spacer means adapted to be interposed between the mining mechanism and the top surface of the gathering head to elevate the mining mechanism with respect to the mine floor for substituting larger cutter means extending down to the mine floor.

17. In a continuous mining machine having a main frame supported by traction means for propelling the mining machine and a mining mechanism at the front end of the mining machine for removing material from the face of a mine as the mining mechanism is advanced into the mine face, a gathering head at the front of the mining machine including gathering means disposed adjacent the floor of the mine for collecting the mined material from the mine floor, means supporting the mining mechanism on the gathering head including a top surface on the gathering head for seating the mining mechanism on the gathering head, said mining mechanism being disposed above the gathering head and being normally seated on the gathering head on said top surface, said gathering head including a frame member disposed behind the mining mechanism, means on said frame member and mining mechanism for connecting the mining mechanism to the frame member for upright adjustment of the mining mechanism relatively to the gathering head and to support the longitudinal thrust of the mining mechanism on the gathering head as it is advanced into the mine face, said mining mechanism including cutter means extending down to the mine floor in front of the gathering means, said cutter means comprising a rotary shaft projecting forwardly from the mining mechanism and a cutter arm extending radially from the rotary shaft, spacer means adapted to be interposed between the mining mechanism and the top surface of the gathering head to elevate the mining mechanism with respect to the gathering head for substitution of a longer cutter arm on the rotary shaft to cut a greater height of material from the mine face.

18. In a continuous mining machine having a main frame supported by traction means for propelling the mining machine and a mining mechanism at the front end of the mining machine for removing material from the face of a mine as the mining mechanism is advanced into the mine face, a gathering head at the front of the mining machine including gathering means disposed adjacent the floor of the mine for collecting the mined material from the mine floor, said gathering means including cutter means to cut an area of the mine face adjacent the floor of the mine, means supporting the mining mechanism on the gathering head including a top surface on the gathering head for seating the mining mechanism on the gathering head, said mining mechanism being disposed above the gathering head and being normally seated on the gathering head on said top surface, said gathering head including a frame member disposed behind the mining mechanism, means on said frame member and mining mechanism for connecting the mining mechanism to the frame member for upright adjustment of the mining mechanism relatively to the gathering head and to support the longitudinal thrust of the mining mechanism on the gathering head as it is advanced into the mine face, said mining mechanism including a forwardly projecting rotary shaft, a cutter arm extending radially from the shaft down to the mine floor in front of the gathering means, a spacer block adapted to be interposed between the mining mechanism and the top surface of the gathering head to elevate the mining mechanism with respect to the gathering head for substitution of a longer cutter arm on the rotary shaft to cut a greater height of material from the mine face, and means for raising the mining mechanism relatively to the gathering head to adjust the mining mechanism cutter arm relatively to the gathering head for removing material from the area of the mine face

above the area from which the cutter means on the gathering means removes material.

19. In a continuous mining machine having a main frame supported by traction means for propelling the mining machine and a mining mechanism at the front of the mining machine for removing material from the face of a mine as the mining mechanism is advanced into the mine face, a gathering head including gathering means for collecting the mined material from the mine floor, means supporting the mining mechanism on the gathering head including a top surface on the gathering head for seating the mining mechanism on the gathering head, said mining mechanism being disposed above the gathering head and being seated on the gathering head on said top surface, said gathering head including a frame member disposed behind the mining mechanism, means on said frame member and mining mechanism connecting the mining mechanism to the frame member to support the longitudinal thrust of the mining mechanism on the gathering head as the mining mechanism is advanced into the mine face, means for supporting the gathering head and the mining mechanism on the front end of the main frame, the last said supporting means including pivot means pivotally connecting the gathering head to the main frame and supporting the gathering head and the mining mechanism on the main frame for transmitting the longitudinal thrust of the mining mechanism from the gathering head to the main frame, means for pivoting the gathering head on said pivot means to adjust the gathering head and the mining mechanism relatively to the main frame, means for driving the gathering means, said driving means including a drive shaft disposed on the axis of the pivot means.

20. In a continuous mining machine having a main frame supported on traction means for propelling the mining machine and a mining mechanism at the forward end of the mining machine for removing material from the face of a mine as the mining mechanism is advanced into the mine face, a gathering head at the front of the mining machine including gathering means disposed adjacent the floor of the mine for collecting the mined material from the mine floor, means adjustably supporting the mining mechanism on the gathering head including a top surface on the gathering head for seating the mining mechanism on the gathering head, said mining mechanism being disposed above the gathering head and being seated on the gathering head on said top surface, said gathering head including a frame member disposed behind the mining mechanism, means on said frame member and mining mechanism connecting the mining mechanism to the frame member to support the longitudinal thrust of the mining mechanism on the gathering head as the mining mechanism is advanced into the mine face, means for raising the mining mechanism to adjust the position thereof relatively to the gathering means, means for connecting the gathering head and the mining mechanism to the front end of the main frame and supporting the gathering head and the mining mechanism on the main frame for transmitting the longitudinal thrust of the mining mechanism from the gathering head to the main frame, said connecting means including pivot means pivotally connecting the gathering head to the main frame, means for pivoting the gathering head on said pivot means to adjust the gathering head and the mining mechanism relatively to the main frame, means for driving the gathering means, said driving means including a drive shaft disposed on the axis of the pivot means.

21. In a continuous mining machine having a main frame supported by traction means for propelling the mining machine and mining mechanism at the forward end of the main frame for removing material from the face of a mine as the mining mechanism is advanced into the mine face, a discharge conveyor on the main frame for moving material along the main frame and discharging material at the rear of the mining machine, said conveyor

comprising a head shaft at the front end of the main frame, a gathering head including gathering means for collecting the mined material from the mine floor and delivering it to the conveyor, means for driving the gathering means, said driving means including a drive shaft disposed on the axis of the conveyor head shaft, driving connections between the drive shaft and the conveyor head shaft for driving the conveyor head shaft, means supporting the mining mechanism on the gathering head including a top surface on the gathering head for seating the mining mechanism on the gathering head, said mining mechanism being disposed above the gathering head and being seated on the gathering head on said top surface, said gathering head including a frame member disposed behind the mining mechanism, means on said frame member and mining mechanism connecting the mining mechanism to the frame member to support the longitudinal thrust of the mining mechanism on the gathering head as the mining mechanism is advanced into the mine face, means for connecting the gathering head and the mining mechanism to the main frame and supporting the gathering head and the mining mechanism on the main frame for transmitting the longitudinal thrust of the mining mechanism from the gathering head to the main frame, said connecting means including pivot means pivotally connecting the gathering head to the main frame on the axis of said head shaft, and means for pivoting the gather-

ing head on said pivot means to adjust the gathering head and the mining mechanism relatively to the main frame.
